UNITED STATES PATENT OFFICE

CREST GUSTAFSON, OF OAKLAND, CALIFORNIA, ASSIGNOR TO E. B. & A. L. STONE COMPANY, OF OAKLAND, CALIFORNIA, A CORPORATION OF CALIFORNIA.

INSIDE FORM FOR SEWER-WORK.

SPECIFICATION forming part of Letters Patent No. 783,575, dated February 28, 1905.

Application filed July 6, 1904. Serial No. 215,487.

To all whom it may concern:

Be it known that I, CREST GUSTAFSON, a citizen of the United States, residing at Oakland, county of Alameda, State of California, have 5 invented certain new and useful Improvements in Inside Forms for Sewer-Work; and I do hereby declare the following to be a full, clear, and exact description of the same.

The present invention relates to an improved 10 inside form for use in connection with the construction of concrete or brick sewers, culverts, or similar structures, the same comprising a series of form-sections detachably connected with means for expanding and contracting the said sections in order to increase 15 and decrease the size of the form circumferentially, the object of the invention being to enable the form to be readily adjusted to the inside circumference of the sewer or culvert 20 to be constructed and quickly released after the formation of one section of the work in order that the form may be easily advanced and placed in position for the construction of an additional section of the work.

To comprehend the invention, reference 25 should be had to the accompanying sheets of drawings, wherein—

Figure 1 is an end view of a completed section of a cylindrical sewer with the form illustrated in adjusted position, the bottom sections of the form being broken away for the purpose of illustrating one style of means for expanding and contracting the form circumferentially. Fig. 2 is a plan view of the bottom sections of the form, which illustrate the style of adjusting means preferably employed where the form is approximately a complete circle. Fig. 3 is a detail perspective view, partly broken, disclosing a completed section 30 of sewer within its trench, the form positioned for an advance section of the work, said form being partly broken away and a section of the completed floor of the sewer advanced beyond the form, the completed floor of the sewer being sectioned on line α α , Fig. 4, of the drawings; and Fig. 4 is an end view of the parts set forth in Fig. 3 of the drawings.

The numeral 1 is used to designate a completed section of an ordinary concrete sewer,

and 2 the floor thereof, that portion of the 50 sewer above the limits 3 of the floor being constructed over the inside form 4, which serves as a supporting inner shell for the material of which the sewer or cylindrical tube is constructed. This form in the present case consists of five distinct sections, of which 5 constitutes the floor-sections, 6 the bench-sections, and 7 the crown-section. However, it must not be understood that a limitation is given 55 as to the number of form-sections that are employed, for such is an immaterial feature of the invention, inasmuch as the said number of sections may be increased or decreased at will.

Preferably each form-section consists of 60 four united ribs 8, so spaced as to produce a section of approximately eight feet in length. The outer face of each rib is curved to conform to the arc of the sewer-section which it is supposed to act as a support for. The ribs 70 of the form-sections, at least those for the bench and crown sections, are provided with an outer face-covering 9, which in the present case consists of a series of parallel wooden strips.

The sections 5 and 6 and 7 are detachably connected by means of the lock-studs 10, which studs engage with the abutting plates or shoulders 11, secured, respectively, to the upper and lower edge of each end rib of sections 6 and 7 and the upper edge of the ribs of section 5. The described locking means are of an exceedingly simple character, and for such reason the same are employed, although any other suitable devices for locking the said sections may be utilized.

The lower or floor sections 5 are preferably skeleton sections, consisting of the curved ribs 8 and the longitudinal rods or plates 12 12'. The lower rod or plate 12 of said opposing sections 5 are adjustably connected by means of the screw-bolts 13, which bolts as screwed inward and outward move the said sections toward and from each other. As these sections are adjusted the entire inside form is 85 contracted or expanded, as the case may be.

It is not required that the floor-sections 5 be provided with an outer face-covering, in-

asmuch as the floor of the concrete-work may be properly shaped without the use of a form.

After the construction of the floor of the sewer the form is required to enable the formation of the remainder of the sewer-wall. The respective form-sections are united or locked together by the lock means and the floor-sections then adjusted toward and from each other by the adjusting means until the circumference of the form is that required for the inside wall of the sewer, which form is left in place until the completion and setting of the sewer-section thereover. While one section of the sewer is setting or hardening, another form is put in place for the formation of an advanced section of the work. The first form within the completed section of the sewer-work is then removed to a position in advance of the second formed section of the work in order that the second advance section of the work may be constructed.

To remove any given form, it is only required to slightly contract the form by adjusting the floor-sections toward each other, when the remaining sections of the form may be readily disconnected or detached. When thus released, each section is passed through the set form of the advance-section of the work for placing together for the formation of a new section of the work.

The essential feature of the present invention resides in the employment of a series of detachably-connected form-sections, with means for expanding and contracting the united sections circumferentially, whereby the form may be quickly and easily adjusted to the required size of the sewer-work and readily taken apart for the purpose of removal. These features it is desired to claim, broadly, whatever form of adjusting means may be employed for contracting and expand-

ing the form-sections circumferentially or whatever style of interlocking means be utilized for connecting the sections.

Having thus described the invention, what is claimed as new, and desired to be protected by Letters Patent, is—

1. An inside form for sewer-work of the character described comprising a series of form-sections detachably connected one to the other and means interposed between the adjacent ends of two of said sections for contracting and expanding the connected sections circumferentially.

2. An inside form for sewer-work of the character described comprising a series of form-sections detachably connected one to the other and a threaded connection interposed between the adjacent ends of two of said sections, said bolt being in threaded engagement with one of said sections, whereby said connected sections may be contracted or expanded circumferentially.

3. An inside form for sewer-work of the character described comprising a series of form-sections, each of said sections being provided at its ends with projecting plates which abut against the corresponding plates of the adjacent sections when the sections are assembled, lock-studs detachably connecting the abutting plates of the adjacent sections, and means interposed between the adjacent ends of two of said sections for expanding and contracting the connected sections circumferentially.

In witness whereof I have hereunto set my hand.

CREST GUSTAFSON.
